Primary Examiner — Lauren R Calve

(57) **CLAIM**

The ornamental design for a pants hanger, as shown and described.

DESCRIPTION

FIG. 1 is a perspective view of a pants hanger showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of a circle portion 9 of FIG. 1;

FIG. 10 is an enlarged view of a circle portion 10 of FIG. 2;

and,

FIG. 11 is an enlarged view of a circle portion 11 of FIG. 7. The broken lines are for the purpose of illustrating portions of the pants hanger and form no part of the claimed design.

1 Claim, 11 Drawing Sheets
